UNITED STATES PATENT OFFICE.

JOSEPH DERK, OF PHILADELPHIA, PENNSYLVANIA, ASSIGNOR TO THE DERK MANUFACTURING COMPANY, OF DOYLESTOWN, PENNSYLVANIA, A CORPORATION OF PENNSYLVANIA.

DESIGN FOR A PILLOW COVER OR SIMILAR ARTICLE.

Application filed September 24, 1927. Serial No. 23,540. Term of patent 3½ years.

To all whom it may concern:

Be it known that I, JOSEPH DERK, a citizen of the United States, residing in the city and county of Philadelphia, State of Pennsylvania, have invented a new, original, and ornamental Design for a Pillow Cover or Similar Article, of which the following is a specification, reference being had to the accompanying drawing, forming part thereof.

The figure is a plan view of a pillow cover or similar article, showing my new and ornamental design.

I claim:

The ornamental design for a pillow cover or similar article, as shown.

JOSEPH DERK.
